CLAIM

The ornamental design for a gaming machine, as shown and described.

DESCRIPTION

FIG. 1 is a front perspective view of a gaming machine showing our new design;

FIG. 2 is a front view thereof;

FIG. 3 is a left side view thereof; and,

FIG. 4 is a right side view thereof.

The unshaded rectangular-shaped region immediately below the display screen is a window, which forms no part of the claimed design. The broken lines depicting the remainder of the gaming machine show features that form no part of the claimed design.
